United States Patent

Des. 242,419
Patented Nov. 23, 1976

242,419

NAPKIN HOLDER

Virginia Stamatovich, 3704 Parson Blvd.,
Flushing, N.Y. 11354

Filed Mar. 31, 1975, Ser. No. 563,379

Term of patent 14 years

Int. Cl. D7—06

U.S. Cl. D7—72

FIG. 1

FIG. 2

FIG. 3

FIG. 4

FIG. 5

FIG. 6

FIG. 1 is a top plan view of a napkin holder, showing my new design;

FIG. 2 is a front elevational view thereof;

FIG. 3 is a left side elevational view thereof;

FIG. 4 is a bottom plan view thereof;

FIG. 5 is a rear elevational view thereof; and

FIG. 6 is a right side elevational view thereof.

I claim:

The ornamental design for a napkin holder, substantially as shown and described.
